UNITED STATES PATENT OFFICE.

DUANE T. DAVIS, OF PANA, ILLINOIS.

GASOLINE-BURNER ATTACHMENT FOR COOK-STOVES.

SPECIFICATION forming part of Letters Patent No. 269,267, dated December 19, 1882.

Application filed October 20, 1882. (No model.)

To all whom it may concern:

Be it known that I, DUANE T. DAVIS, a citizen of the United States, residing at Pana, in the county of Christian and State of Illinois, 5 have invented a new and useful Improvement in Gasoline-Burner Attachments for Cook-Stoves, of which the following is a specification.

My invention relates to certain new and useful improvements in devices for connecting vapor-burners to cook-stoves; and it consists in an improvement in the construction of the bridge commonly used in stoves to support the covers by casting lugs or hooks on its under side, which will, when the bridge is placed in position, hook under the permanent top plate of the stove and prevent its rocking or tipping when by accident the stand-pipe which supports the fluid tank or reservoir is jarred or struck, 15 the said stand-pipe being secured to the bridge by check-nuts fitted to the outside of the stand-pipe on either side of the bridge, securely uniting the bridge and stand-pipe, so that they may both be lifted off at once. I attain these objects by the device illustrated in the accompanying drawings, in which—

Figure 1 represents a top plan view of a cook-stove with the burners properly connected. Fig. 2 is a side elevation of the bridge and 30 burner, showing the manner of securing the bridge to the stand-pipe, also showing the lugs or hooks by which it is secured to the top of the stove.

Similar letters refer to similar parts throughout the several views.

A represents the top of the stove, and B B the improved bridges.

C is the stand-pipe, surmounted by the ordinary fluid-reservoir.

40 c c represent the burners, which are so arranged as to stand about in the center of the opening or pot-hole of any ordinary cook-stove.

c' c' are check-nuts, by means of which the bridge is secured to the stand-pipe.

45 b b are the lugs or hooks which extend under

the permanent top plate of the stove and prevent the bridge from becoming displaced.

When it is desired to use four burners the connection is made with the stand-pipe, as shown in Fig. 1, the connection of the stand-pipe and forward bridge being the same as in the use of two burners.

To remove the burners from the stove all that is required is to grasp the stand-pipe and raise the rear end of the bridge first, thus releasing the lugs or hooks, and the whole can be removed in an instant. The attachment of the bridge can be made to any of the ordinary two-burner gasoline-stoves, and the burners placed in the cook-stoves in the manner shown, 60 which has proved to be exceedingly advantageous, as it takes up less space and is more convenient for general use, also insuring entire safety.

Having thus described my invention, what 65 I believe to be new, and desire to secure by Letters Patent, is—

1. As an improved article of manufacture, a device for connecting vapor-burners to a cook-stove, consisting of the bridge B, having a hole 70 to admit the stand-pipe, which is secured thereto by check-nuts or otherwise, and the lugs or hooks on the under side at the forward end of said bridge for the purpose of securely holding the bridge in place and preventing its rocking, substantially as shown and described.

2. A removable suitably-apertured stove-bridge provided with lugs or projections on one side thereof, said lugs being adapted to pass under a permanent portion of the stove-top, in combination with a fluid-reservoir and suitable burners, and a connecting-pipe passing through the aperture in said bridge, and provided with upper and lower check or clamping nuts, whereby it is rigidly attached thereto, 80 substantially as set forth.

DUANE T. DAVIS.
